CLAIM

The ornamental design for a display screen with graphical user interface, as shown and described.

DESCRIPTION

FIG. 1 is a front elevation view of a portion of a display screen with graphical user interface, showing the new design.

FIG. 2 is a front elevation view of a second embodiment of the portion of a display screen with graphical user interface. FIG. 3 is a front elevation view of a third embodiment of the portion of a display screen with graphical user interface. FIG. 4 is a front elevation view of a fourth embodiment of the portion of a display screen with graphical user interface. FIG. 5 is a front elevation view of a fifth embodiment of the portion of a display screen with graphical user interface; and,

FIG. 6 is a front elevation view of a sixth embodiment of the portion of a display screen with graphical user interface. The dotted grid of concentric rings is part of the claimed design. The outer broken lines represent the boundary of the portion of a display screen with graphical user interface, and form no part of the claimed design. The other broken lines represent other elements of the portion of a display screen that form no part of the claimed design.
